UNITED STATES PATENT OFFICE.

ANGELO RUSSO, OF BURLINGTON, MASSACHUSETTS.

LOCK.

Application filed June 4, 1926. Serial No. 113,720.

The present invention relates to locks and has for its object to provide a lock which is reliable in action and not easily tampered with by unauthorized persons, and which is 5 simple in construction, and readily operated under intensive conditions.

Another very important object of the invention is the provision of a lock which affords protection against the opening of a 10 door even though a person has a key to the lock.

Another important object of the invention is to provide a novel combined night latch and cylinder lock wherein a novel connection is provided between the two. 15

With the above and numerous other objects in view, the invention consists in the construction and arrangement of parts as will be hereinafter more fully described and 20 claimed.

In the drawing:—

Figure 1 shows a fragmentary sectional view of a portion of a door with my improved lock mechanism attached thereto,

Fig. 2 is a plan view of the door showing the outer portion of the cylinder lock,

Fig. 3 is an elevation of the latch structure,

Fig. 4 is an elevation thereof with the 30 closure plate removed,

Fig. 5 is a sectional view taken transversely through the latch casing substantially on the line 5—5 of Fig. 3,

Fig. 6 is a transverse section substantially 35 on the line 6—6 of Fig. 4,

Fig. 7 is an enlarged detail sectional view taken substantially on the line 7—7 of Fig. 1,

Fig. 8 is an end elevation of the roll-back stem,

Fig. 9 is an end elevation of the key operated member for operating the roll-back stem. 40

Referring to the drawing in detail, it will be seen that 10 represents a door and 11 the door jamb, said door being provided with 45 a suitable opening 12 for the accommodation of a tumbler barrel or cylinder 13 which may be of any suitable construction and which may contain tumbler mechanism of any known type. The cylinder 13 is secured in opposite positions in any convenient way as for instance by means of screws 14 co-operating with plate 15.

The numeral 16 denotes the rotatable member in the barrel 13 which is key operated, said key being indicated by the

numeral 17. The inner end of this rotatable member 16 is formed with a pair of bores 18 for receiving pins 19 on a plate 20. The pins 19 extend from one face of the plate 20 while from the other face thereof extends 60 a stem 22. The cylindrical extension 23 formed on the inner end of the bar or cylinder 13, receives slidably, the hood portion 25 of a roll-back stem 26. A suitable cap 28 is held on the cylindrical extension 23 by a 65 set screw 29, and has an opening through which a portion of the head 25 is slidable. Spring 30 is mounted in the cylindrical extension 23 and impinges against the head 25 and against the plate 20, normally holding 70 them in the position shown to advantage in Fig. 7 of the drawing. The inner end of the head is provided with a groove 31. When the key 17 is passed into the barrel 16, that is, the rotatable portion of the lock 75 heretofore indicated, said key presses against the plate 20, compresses the spring 30, until the stem 22 is disposed in the groove 31, so that when the key is turned, the roll-back 80 stem 26 will be turned therewith.

The latch structure is housed in a casing 33 of any preferred construction, including a closure plate 34 which is held in engagement with the casing 33 by a screw 35 and engaging in the lug 36 formed interiorly 85 of the casing. A latch 37 is movable through an opening 38 in one end wall of the casing 33 and is formed integrally on a shank 39. A rack frame 40 is formed integrally on the shank 39 at the other end thereof, and one side is provided with interior rack teeth 41. The rack frame 40 is movable between lugs 42 formed in the casing. The forward movement of the rack frame is limited by 90 a stop pin 43 formed in the casing, and obviously this pin also limits the forward movement of the shank 39 and the latch 37. 95

Stop extensions 44 are formed on the end of the rack frame 40 to extend laterally therefrom and engage the lug 42 for also 100 limiting the movement of said rack frame toward the end wall having the opening 38. A spring 45 impinges against one of the extensions 44 and against the other end of the casing so as to normally hold the latch 37 105 extended for engagement with the keeper 46. The closure plate 34 is provided with a rib terminating adjacent the spring so as to assist in preventing the displacement thereof. A roll-back shaft 38 is journaled in the cas- 110

ing 33 and has a gear 49 formed thereon meshing with the rack teeth 41. One end of this shaft terminates with a slot 50 for receiving the end of the roll back stem 7.

5 From the description as it has thus far progressed, it will be readily apparent that by inserting a key in the rotatable portion 16 of the cylinder lock 13, that the plate 20 may be pushed inwardly to engage the 10 stem 22 thereof in the groove 31 of the head 25 of the roll-back stem 26, so that when the key is turned, said roll-back stem 26 is turned for rotating the roll-back shaft 48 and the gear 49 for moving the rack 40, the 15 shank 39, and the latch 37 inwardly of the casing 33. Thus the door may be unlocked from the exterior thereof.

In order to unlock the door from the inside thereof, I provide a shaft 51 rotatable 20 in the casing and having a knob 52 on its exterior end and a crank 53 on its interior end. Said crank 53 is engageable with the forward edge of the rack frame 40 so as to push the same against the tension of the spring 45 and move the latch into an unlocked position. This crank may be operated to such an extent that it will extend longitudinally of the casing in one direction for holding the latch unlocked while it may 25 be rotated to extend in the opposite direction toward the latch 37 to engage the inner end thereof as is clearly shown in Fig. 1, for preventing the latch from being opened. When the crank is in this position as described, it will be seen that said latch can-

not be opened even by the insertion of the key and the rotation thereof in the cylinder lock 13.

It is thought that the construction, operation, and advantages of this invention will now be clearly understood by those skilled in this art without a more detailed description thereof. The present embodiment of the invention has been disclosed in detail merely by way of example, since in actual practice, it affords the features of advantage enumerated as desirable in the statement of the invention and the above description. Various changes in the specific form shown and described may be made within the scope 45 of the claim without departing from the spirit of my invention.

Having thus described my invention, what I claim as new is:—

In combination with a cylinder lock; 55 wherein the lock is provided with a key operated rotatable part; a cylindrical extension extending from the lock, a plate having pins projecting therefrom into recesses provided in said rotatable part, and provided with a stem, a roll back stem having a head rotatable in the cylindrical extension, means for holding the head in the cylindrical extension, said head being provided with a slot for receiving the stem of the plate, and a 60 spring in the cylindrical extension impinged against the plate and against the head.

In testimony whereof I affix my signature.

ANGELO RUSSO.
